UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A TABLE.

SPECIFICATION forming part of Design No. 24,974, dated December 10, 1895.

Application filed May 11, 1895. Serial No. 548,998. Term of patent 7 years.

To all whom it may concern:

Be it known that I, LOTHAR VON GRAVE, a citizen of the United States, residing at Wallingford, New Haven county, State of Connecticut, have invented and produced a new and original Design for a Table, of which the following is a specification.

The leading feature of my design is a table of essentially the configuration and representation shown in the accompanying drawings, in which—

Figure 1 is a view in perspective of a table embodying my design, and Fig. 2 is a plan view of so much of the top frame thereof as is essential to exhibiting my design.

In the drawings, A is a table-top surrounded by a frame B, consisting of an inner rectilinear border b , consisting of the ornamental beads $b' b^2 b^3$ surrounded by an outer open-work border conforming to the contour thereof and con-

sisting of leaf-like ornaments $c d e f g i j$, each consisting of an oak-leaf-like ornament a' , a scroll-like stem a^2 extending from the base of the leaf a' and curved reversely to meet the leaf again, and meeting the stem a^3 of the adjacent ornament a' , and a curled scroll-like projection a^4 extending from the top of the leaf a' and curled reversely toward the leaf a' and meeting the scroll a^5 of the adjacent leaf a' at the corner of the frame, so as to form an open-work curvilinear corner ornament a^6 . Projecting from the frame or border are ogee-shaped legs C.

What I claim is—

The design for a table, substantially as herein shown and described.

LOTHAR VON GRAVE.
